TELESCOPIC SIGHT MOUNT

Freeman O. Peterson, Warren, Pa.

Application June 17, 1937, Serial No. 148,817

17 Claims. (Cl. 42—1)

The invention aims to provide a new and improved means for mounting a telescopic sight upon a rifle in such manner that said sight may be quickly and easily attached and removed, will occupy a relatively low position on the rifle, will become automatically alined when applied, will require no side supports and when removed will leave the top of the rifle clear for the ordinary rear sight.

10 With the foregoing and minor objects in view, the invention resides in the novel subject matter hereinafter described and claimed, description being accomplished by reference to the accompanying drawing.

15 Fig. 1 is a side elevation showing a portion of a rifle equipped with the improved mounting means for a telescopic sight.

Fig. 2 is a top plan view of the sight mount, part of it broken away and in section.

20 Fig. 3 is an enlarged side elevation of the mount engaged with the rifle, portions of the latter being in section.

Fig. 4 is a longitudinal sectional view on line 4—4 of Fig. 2.

25 Fig. 5 is a transverse sectional view on line 5—5 of Fig. 3.

Fig. 6 is a transverse sectional view on line 6—6 of Fig. 3.

30 A preferred construction has been illustrated and will be rather specifically described, with the understanding however, that within the scope of the invention as claimed, variations may be made.

35 The receiver 6 of the rifle is provided with the longitudinal loading recess 7 opening through its upper side. I form the front end wall of this recess 7 with a shallow socket 8 which is preferably about hemispherical, said socket opening rearwardly. In the rear end wall of the recess 7, I form a cavity 9 which opens both forwardly and through the upper side of the receiver 6, and at opposite sides of said cavity 9, I form threaded openings 10 in the receiver. No other variations in the rifle construction are necessary to attach 45 a telescopic sight 11 thereto with the aid of the present invention.

50 I provide a horizontally elongated sight-mounting member 12 upon which the sight 11 is secured by curved clamps 13, said clamps being fastened upon the end portions of the mounting member 12, by screws or the like 14. The front end of the member or body 12 is provided with a forwardly projecting stud 15 which is preferably about hemispherical for snug reception in the 55 socket 8. The rear end of the body 12 is pro-

vided with a downwardly projecting lug 16 for snug reception in the cavity 9, and two attaching screws 17 are suitably swiveled in said rear end of said body 12, for reception in the threaded openings 10, loss of said screws being prevented by providing them with stop collars or shoulders 18 and by threading stop screws 19 into the rear end of the body 12, the parts 18 and 19 being normally spaced apart such a distance that either screw 17 may be entirely disengaged 10 from the threaded opening 10 before the other of the screws 17 is started from its respective opening, thus obviating injury to screw threads which would inevitably result if no space were allowed between 18 and 19, necessitating partial 15 unscrewing of one screw, then partial unscrewing of the other, and so on until both screws were disengaged from the openings.

20 The stud 15 is preferably formed by the front end of a cylindrical pin 20 which is tightly slidable in a bore 21 in the front portion of the body 12, said pin abutting the front end of a screw 22 which is forwardly threaded into said bore. After initially adjusting the device to the gun, it is seldom necessary to touch the screw 22, but if 25 any looseness should occur, said screw may be tightened to force the pin 20 forwardly sufficiently to overcome such looseness. To insure tight fitting of parts when the screws 17 are tightened, I bevel the rear end of the lug 16 as 30 shown at 23 and similarly bevel the contacting wall 24 of the cavity 9. After inserting the front portion of the body 12 partially in the recess 9 and engaging its stud 15 with the socket 8, and downwardly swinging the rear end of said body, 35 the screws 17 may be threaded into place, and during the final tightening of these screws, the bevels 23 and 24 act as cam surfaces to forwardly force the body 12, thus holding the stud 15 engaged with the socket 8 with extreme tightness, 40 overcoming any vibration and inaccuracies.

45 The body 12 is preferably of the general shape shown, with its intermediate portion somewhat narrower than its end portions. The entire body is longitudinally channeled in its upper side as 50 shown at 25, and machined seats 26 are employed for the telescopic sight 11, said seats co-acting with the clamps or the like 13 in tightly holding said sight. Upon its lower side, the intermediate portion of the body 12 is preferably 55 of substantially V-shape. At the rear end of the body, the latter is of the shape shown in Fig. 5, and the lower side of said body, at the front end thereof, may well be provided with a longitudinal boss 27 in which a portion of the bore 21 55

- is formed. The upper side of the body is preferably beveled at its longitudinal edge portions so as to not interfere with the ends 28 of the straps or the like 13. At its rear extremity, the body 5 12 is preferably provided with a T-head 29 formed integrally therewith, the attaching screws 17 being rotatably mounted in the ends of this T-head and the lug 16 being integral with the lower side of said T-head.
- 10 To attach the device, it is simply necessary to engage the stud 15 with the socket 8 and drive the screws 17 tightly into the openings 10, and by a reversal of these operations, the mount may be removed with equal ease. The telescope 15 sight 11 may remain engaged with the mount 12 to be applied and removed bodily with the latter and it will be observed that the construction is such as to insure proper alignment when attaching the mount to the gun. Moreover, the sight 20 will then occupy a relatively low position and will be properly mounted without the necessity of any side arms or the like. The amount is of course sufficiently high to prevent it from interfering with loading, it being customary with telescope-equipped guns to single-load by hand instead of using a clip carrying several rounds. When the mount and the sight are detached, the entire upper portion of the gun is left unobstructed for use of the usual sight.
- 25 30 Excellent results have been attained from the construction shown and described and it is therefore preferably followed. However, within the scope of the invention as claimed, variations may be made, as above stated.
- 35 I claim:
1. In a sight mounting means, a rifle having a receiver provided with an upwardly open longitudinal loading recess, one end wall of said recess being provided with a shallow socket which opens 40 toward the other end wall of said recess; an elongated sight-mounting body extending longitudinally of the upper portion of said loading recess but sufficiently high to prevent interference with loading, one end of said body being provided with 45 a stud snugly received in said socket, and releasable means for securing the other end of said body to said receiver.
  2. In a sight mounting means, a rifle having a receiver provided with an upwardly open longitudinal loading recess, one end wall of said recess being provided with a shallow socket which opens 50 toward the other end wall of said recess, said other end wall being provided with a cavity which opens both upwardly and toward said one end wall; an elongated sight-mounting body extending longitudinally of the upper portion of said loading recess but sufficiently high to prevent interference with loading, one end of said body being provided with a stud snugly received in 55 said shallow socket, the other end of said body being provided with a downwardly projecting lug snugly received in said cavity, and releasable means for securing said other end of said body to said receiver.
  3. In a sight mounting means, a rifle having a receiver provided with an upwardly open longitudinal loading recess, one end wall of said recess being provided with a shallow socket which opens 60 toward the other end wall of said recess; an elongated sight-mounting body extending longitudinally of the upper portion of said loading recess but sufficiently high to prevent interference with loading, one end of said body being provided with a stud snugly received in said socket, means 65 at the other end of said body for downwardly
  - moving the same solidly against said receiver, and coacting means on said other end of said body and said receiver for forcing said body longitudinally to tightly seat said stud in said socket when said means for downwardly moving said other end of said body is tightened.
  4. In a sight mounting means, a rifle having a receiver provided with an upwardly open longitudinal loading recess, one end wall of said recess being provided with a shallow socket which opens 10 toward the other end wall of said recess, said other end wall being provided with a cavity which opens both upwardly and toward said one end wall; an elongated sight-mounting body extending longitudinally of the upper portion of said loading recess but sufficiently high to prevent interference with loading, one end of said body being provided with a stud snugly received in said shallow socket, the other end of said body being provided with a downwardly projecting lug 15 snugly received in said cavity, said lug and a wall of said cavity being provided with coacting cam faces for forcing said body toward said one end wall when said other end of said body is forced downwardly, and attaching means connecting 20 said other end of said body with said receiver for downwardly forcing the former tightly against said receiver, thereby causing said cam faces to longitudinally force said body to tightly hold said stud in said shallow socket.
  5. In a sight mounting means for a rifle, an elongated sight-mounting body, connecting means between one end of said body and the rifle engageable and disengageable by longitudinal movement of said body, means for downwardly 25 moving the other end of said body solidly against the rifle, and coacting means on said body and rifle for longitudinally moving the former to tightly engage said connecting means as said means for downwardly moving said body against 30 the rifle is tightened.
  6. In a sight mounting means for a rifle, an elongated sight-mounting body, a stud-and-socket-connection between the rifle and one end of said body engageable and disengageable by 40 longitudinal movement of said body, means for downwardly moving the other end of said body solidly against the rifle, and coacting means on said body and rifle for forcing said body longitudinally to tightly engage said stud-and-socket-connection as said means for downwardly moving 45 said other end of said body is tightened.
  7. In a sight mounting means for a rifle, an elongated sight-mounting body, connecting means between one end of said body and the rifle engageable and disengageable by longitudinal movement of said body, and means for downwardly moving the other end of said body solidly 50 against the rifle, said other end of said body being provided with a downwardly projecting lug and the rifle being provided with a cavity snugly receiving said lug, said lug and a wall of said cavity being provided with coacting cam faces for longitudinally moving said body to tightly engage said connecting means as said means for downwardly moving said other end of said body is tightened.
  8. In a sight mounting means for a rifle, an elongated sight-mounting body having a longitudinally projecting rifle-engaging stud at one 60 end, and a rifle-engaging attaching screw passing through the other end of said body for drawing said other end inwardly toward and holding it solidly against the rifle.
  9. In a sight mounting means for a rifle, an 70

- elongated sight-mounting body having a longitudinally projecting rifle-engaging stud at one end, a rifle-engaging attaching screw passing through the other end of said body for drawing said other end inwardly toward the rifle, and a rifle-engaging cam on said body for longitudinally shifting the same to tightly seat said stud as said screw is tightened.
10. A structure as specified in claim 8; said stud being formed by the end of a pin, said body being provided with a longitudinal bore in which said pin is received, and means for adjusting said pin longitudinally in said bore.
11. In a sight mounting means for a rifle, an elongated body, one end of said body being provided with a longitudinally projecting rifle-engaging stud, the other end of said body being provided with a T-head to rest upon a portion of the rifle, said T-head having openings therethrough and rifle-engaging attaching-screws rotatably mounted in said openings.
12. In a sight mounting means for a rifle, an elongated body, one end of said body being provided with a longitudinally projecting rifle-engaging stud, the other end of said body being provided with a T-head to rest upon a portion of the rifle and being provided with a downwardly projecting rifle-engaging lug at the intermediate portion of said T-head, said T-head having openings therethrough and rifle-engaging attaching screws rotatably mounted in said openings.
13. In a sight mounting means for a rifle, an elongated body, one end of said body being provided with a longitudinally projecting rifle-engaging stud, the other end of said body being provided with a T-head to rest upon a portion of the rifle and being provided with a downwardly projecting rifle-engaging lug at the intermediate portion of said T-head, said T-head having openings therethrough and rifle-engaging attaching screws rotatably mounted in said openings, the end of said lug remote from said stud being beveled for the purpose set forth.
14. In a sight attaching means, a rifle having a receiver and a longitudinal loading recess open-
- ing through the upper side of said receiver, one end wall of said loading recess being provided with a shallow socket which opens toward the other end wall of said recess to receive a portion of a sight mount, said receiver having provision near the other end of said loading recess for facilitating the securing of another portion of the mount.
15. In a sight attaching means, a rifle having a receiver and a longitudinal loading recess opening through the upper side of said receiver, one end wall of said loading recess being provided with a cavity which opens toward the other end wall of said loading recess and opens also through the upper side of said receiver to receive a portion of a sight mount, said receiver having provision at the other end of said loading recess for facilitating the securing of another portion of the mount.
16. In a sight attaching means, a rifle having a receiver and a longitudinal loading recess opening through the upper side of said receiver, one end wall of said loading recess being provided with a shallow socket which opens toward the other end wall of said loading recess to receive a portion of a sight mount, the other end wall of said loading recess being provided with a cavity which opens toward said one wall of said recess and also opens through the upper side of said receiver to receive another portion of the sight mount.
17. In a sight attaching means, a rifle having a receiver and a longitudinal loading recess opening through the upper side of said receiver, one end wall of said loading recess being provided with a shallow socket which opens toward the other end wall of said loading recess to receive a portion of a sight mount, the other end wall of said loading recess being provided with a cavity which opens toward said one wall of said recess and also opens through the upper side of said receiver to receive another portion of the sight mount, the end of said cavity remote from said socket being beveled for the purpose set forth.

FREEMAN O. PETERSON.
